DELAYED ACTION MECHANISM FOR SNAP SWITCHES

Ewing L. Sharp, Los Angeles, Calif., assignor to
Victory Switch Company, Los Angeles, Calif.

Application January 2, 1940, Serial No. 312,011

6 Claims. (Cl. 200—34)

The present invention relates to improvements in switches and particularly to a snap action electric switch having an alternate delayed snap action.

The present invention is in certain particulars an improvement on an application for patent for Delayed action switches, Ser. Number 279,137, filed June 14, 1939, which matured in Patent #2,188,685; the present application and the patent just referred to having a common assignee of the entire title to each invention.

One of the important objects of the invention is to provide, in a device of the above character, an electric switch having improved delay action means manually adjustable from an inoperative to an operative position, thereby delaying the opening of the circuit which results from the next operation of the switch for opening the circuit, said delay action means thereupon automatically restoring itself to its inoperative position.

Another important object of the invention is to improve upon the mechanism which causes the delay action.

Still another object of the invention is to provide, in a device of the character stated, an additionally improved toggle acting and push button combination for placing the delay action mechanism into its operative position.

Yet another object of the invention is to provide in a combination snap and delayed action switch additionally improved means for assuring a more positive snap action upon completion of the delayed operation of the switch.

Yet a further object resides in the improvement of the casing whereby certain movable parts in the above referred to co-pending application have been omitted and the construction of other parts simplified and improved upon.

Still further objects, features, and advantages of invention will hereinafter appear.

Referring to the drawings wherein is shown a preferred embodiment of the invention as now reduced in practice.

Fig. 1 is a front elevation of the improved structure assembled within its housing, a portion of the face plate being broken away to show underlying structures. In said figure two wires and a lamp are diagrammatically shown.

Fig. 2 is a vertical mid-section taken on line 2—2 of Fig. 1 showing the toggle lever in the "on" and "off" positions, a fragment of the conductor conduit is included in this view.

Fig. 3 is an enlarged vertical mid-section showing the switch "on" or in circuit closed position,

the dotted lines indicating the position of the parts for snap action and the full line indicating the position of the parts set in readiness for a delayed action.

Fig. 4 is a section similar to Fig. 3 but with the parts in the "off" or open circuit position which they occupy at the completion of the functioning of the delay acting mechanism. The face plate is omitted in Figs. 3 and 4.

Fig. 5 is a view taken on approximately the plane indicated by the line 5—5 of Fig. 3.

Fig. 6 is a vertical section taken on line 6—6 of Fig. 5, the dash-pot cylinder being omitted.

Fig. 7 is a transverse section taken on line 7—7 of Figs. 5 and 6.

Fig. 8 is a transverse section taken on line 8—8 of Fig. 5.

Fig. 9 is an enlarged perspective view of the parts which control the delayed action of the switch.

Referring in detail to the drawings, the switch box 1 has a bottom wall 2 having a circular recess 3 within which is fitted the upper portion of an open-mouthed cup-shaped piston cylinder 4. Said piston cylinder has an external peripheral rib or bead 5 which abuts against the bottom portion of the box 1 and of its bottom wall 2 when the cup-shaped member 4 is in its mounted position, at which time said member is supported by a set screw 6 which extends through the face strap 7 and with a screw-threaded relation through a downward extension 2a of the aforesaid wall 2, the rib 5 being thickened at 5a and having a beveled lower face 5b, the screw having a tapered end portion which engages said face 5b with a wedging fit to support the member 4 in a secure manner.

A piston head 8 operates within the cylinder 4, said piston having a flattened stem 9 furnished with a longitudinal cam slot 10, said slot being somewhat arcuate and having in the front side of its upper end portion a recess, the lower portion of which forms a seat 11. The upper back portion of stem 9 has a cam portion 9a which, as the piston descends, is acted upon by an abutment lug 9b that projects internally from the back wall 12 of the casing, said abutment serving to restore the descending piston stem to its forward position. Said piston 8 is furnished with a gasket 8g shaped as a shallow cup, the peripheral wall of which is sufficiently flared to allow the piston as a whole to swing sufficiently to operate as hereinafter set forth. The upward travel of the piston stem is arrested by the

bumper lug 13a carried by the top wall 13 of the switch box.

As well shown in plan in Fig. 7 and in elevation (the face plate being removed) in Fig. 5, the upper part of each side wall 15 of the casing has secured to it, by a binding screw 16, an L-shaped conductor strip 17, fitted into the adjacent back corner of the casing and carrying a pair of terminal arms 18 which constitute stationary terminal parts of a knife blade switch. Lead wires 19 are shown to supply current to said parts 17 and 18. The piston stem is secured to its head at a backward inclination, as shown.

The blade portion 20 of the switch has a deflected free end portion 20a to cooperate with the pair 18 of switch terminals at one side of the casing, and the adjacent portion of a swinging arm 21 which carries said blade 20 likewise cooperates with the other pair of switch terminals. The body portion of said arm 21 is somewhat J-shaped and at, or a little below, its mid-length is swingably supported by a pivot pin 22 which bridges the slot 23 of a lug 24 formed within a corner of the casing, said slot guiding the swinging movements of said arm 21.

The switch assembly further includes a toggle switch lever 25 which is externally similar to the conventional switch lever of its type except that the trunnions 26 whereby it is mounted are eccentrically positioned in relation to said lever. Said trunnions rest in seats formed by notches 26a in the front edges of the casing side walls 15 and are kept in place by the face strap 7 when the latter is attached by its screws 7s. Adjacent to one of its trunnions said lever 25 carries conventional stop wings 25w.

The means for retarding the circuit opening action of the switch includes an elongated button 36 which operates in a guide passage 37 that extends axially through the toggle lever 25 and which has an enlarged inner end portion 37a within the bell portion 25x of the toggle lever. Within said enlargement 37a is a workably fitted head 40 which is rigidly connected with the button 36 by means of a stem 41. Said head 40 carries a backward extension 42 having an apertured end portion 43 to which is attached one end of a spiral spring 44.

By preference, and as shown, the head 40 is a metal plate shaped as a stocky L, the stem 41 which unites said head to the button 36 being integral with the head so as to be stamped out therewith. That arm of the L which carries the extension 42 also carries at its lower edge a tappet finger 45 which is at a right angle to the head 40. Said tappet finger 45 is positioned to act upon a slideable engager 46 which, in turn, is positioned to engage the piston stem 9 to swing it back to its original position after said stem has been swung in the reverse direction in the manner hereinafter described.

The slideable engager 46, preferably of a sheet metal character, has a body portion 47, (see Fig. 9), which carries a guide arm, or mounting arm 48, which reciprocates in a guide groove 49 provided for it in the interior face of one of the casing side walls 15, said groove having a contacted mouth 49a (Fig. 5) which keeps said arm 48 in place.

In addition to its mounting arm 48, the engager 46 carries an L-shaped push arm 51 which is positioned to act upon the piston stem 9 to swing the upper end of the latter backwardly to the full-line position of Fig. 3, said arm 51 for this purpose at times contacting a forwardly pro-

jecting rise 52 near the upper end of said stem 9. The purpose of giving the upper part of the piston stem this backward swing is to cause a piston depressing pin or finger 55, see Fig. 3, (which is operated by means which will next be described) to be brought from the upper seat 11x into a superjacent relation to the seat 11 (see Fig. 4) in the upper part of the piston stem.

A swingable yoke 56 (see Fig. 5) has its arms 10 furnished with outwardly directed trunnions 57 having bearings within seats formed by the inner ends of internal grooves 58 led in from the front edges of the side walls of the casing. At 15 its free end, said yoke carries the already mentioned finger 55, which extends parallel to the axis about which the yoke swings. Said yoke is suitably shaped in its free end portion to have the back end portion of the already mentioned spring 44 held in an operative relation to the 20 yoke in order that said spring may act upon the yoke at times to cause its finger 55 to depress the piston in opposition to air contained in the cylinder 4. All portions of the slot 10 are considerably wider than the diameter of the pin 55, said 25 slot having at about its mid-length a forward swell 10w wherein said pin rests when it is in its lowest position.

Referring again to the J-shaped switch arm 21 which is operable to control the circuit between the switch terminals comprised by the two 30 pairs of contact arms 18, said arm 21 is swung in a direction to open the circuit, by reason of being contacted by the yoke 56 as the latter swings downwardly, urged by spring 44, at times 35 freely and at other times in opposition to the retarded piston when the finger 55 of the said yoke is superimposed upon the seat 11 in the slotted part of the piston stem.

In such instance the free end portion of said 40 yoke strikes against the inner side of the hook portion 59 of the arm 21 to swing the arm 21 about its pivot 22 in a direction to open the circuit with a snap action. When the yoke 56 swings upwardly, its free end portion strikes the 45 upper cam face 59a of the J-shaped arm and closes the switch with a snap action. When the toggle lever 25 is in the "up" position, the spring 44 is positioned, by compression, to maintain the yoke 56 in its "up" position, to which position 50 it has brought said yoke as a result of the upswinging of said lever; and when said lever is in the "down" position, said spring is positioned, 55 by compression to maintain said yoke in its "down" position, to which position it has brought said yoke as a result of the downswinging of said lever.

The piston cylinder or cup 4 has a thickened bottom portion 60 furnished with a screw-threaded central air inlet passage 61. Said passage is flared at its lower end to cooperate with a screw 62 having a conical head 63. A spongy rubber gasket 74 is positioned between the head of said screw and the flared mouth portion of said passage 61. This gasket supplies the traction force upon the screw requisite to maintain it in the adjusted position, the amount of air leak through the passage depending upon the amount of compression. The threaded connection between the screw and passage into which 60 it screws forms a sufficiently loose fit to provide adequate air leakage for the most rapid piston movement desired.

As the stem 9 of the piston is secured to the piston head at the backward inclination to the axis of said head, the back side of said head is

considerably higher than its front side, when the piston stem is in its forwardly swung position as it always is when said head is at the downward limit of its travel. This construction facilitates the upward movement of the piston because it causes air from above the piston head to pass more readily down its front and back sides.

Speaking briefly of conventional parts not yet mentioned, the face plate 75 is of a well-known type and is held in place by screws 76. A conductor conduit 77 is shown leading into the bottom portion of the casing, but the conventional wiring, which occupies the space shown therefor, is omitted.

Operation

The cycle of operation begins with the toggle lever 25 in the down or "off" position. By pushing said lever up, the spring 44, in relation to its point of attachment to the toggle lever, is changed from its extended condition and downwardly inclined position shown in Fig. 4 to an upwardly inclined position, more compressed condition, whence its coils quickly expand causing it to swing the free end of the yoke 56 upwardly till said yoke is arrested in its upward movement by reason of its finger 55 striking against the upper end of the slot 10 of the piston stem, assuming that said stem is then in its upper position wherein its upper end engages the abutment or stop 13a.

During its upward swing, the free end portion of the yoke, near one of its sides, exerts a cam action upon the face 59a of the arm 21 which carries the switch blade 20, causing the upper end of said arm to swing backwardly and thus move said blade into the circuit completing position.

The upward swinging of the toggle lever 25 will always cause the operation which has just been described, except, in case the piston 9 is in its down position the yoke pin 55 will first travel from the mid-length portion of slot 10 (see Fig. 4) to a contacting relation to the upper end of said slot, and then, during the final part of its upward movement said yoke pin will carry with it the piston stem until the latter is brought to its uppermost position.

The remaining portion of the cycle of operation is effected by the down throw of the toggle lever 25, which causes the switch blade 21 to be moved to the open circuit portion, either immediately, in case the button 36 is not depressed, or else in a delayed manner, in case the button 36 has previously been depressed to the full line position of Fig. 3. But whether an immediate or delayed circuit opening operation takes place this is effected by the spring 44 being thrown off center in a downward direction as shown in Fig. 4. If the button 36 has not been depressed before this is done, the yoke pin 55 remains in the body portion of the slot 10 of the piston stem and glides freely down said slot without delaying the circuit opening movement of the switch. When, however, the button 36 is depressed before the downward throwing of the toggle arm, said button moves the stem 41 and head 40 backwardly and causes the tappet finger 45 carried by said head to slide the engager backwardly, which, in turn, by means of its arm 51, to press backwardly upon the upper portion of the piston stem 9 and brings its seat 11 into a subjacent relation to the yoke pin 55, so that the downward movement of said pin will be opposed and

retarded by the dash pot structure of which said piston stem forms a part.

It is to be observed that the recess which forms the seat 11 in the upper portion of the piston stem slot 10 is located slightly below the upper end of said slot. Hence, from the view point of operation, the shallow upper seat 11x results. When the toggle lever 25 is up the finger 55 fits within said seat 11x and causes the piston to remain positively in its forward position until it is swung backwardly in the manner which has been described. Owing to the shallow character of said seat 11x, the presence of pin 55 therein offers no objectionable impediment to the backswinging of the piston stem preparatory to its functioning to delay the opening of the circuit.

It should be understood that the present disclosure is for the purpose of illustration only and that this invention includes all modifications and equivalents which fall within the scope of the subject matter claimed.

What is claimed is:

1. Means for retarding the circuit-opening action of an electric switch, comprising a casing, a dash-pot cylinder in the lower portion of said casing, a piston stem having a head operating in said cylinder, said piston stem having through it a longitudinal slot, there being an upwardly directed seat occupying the lower portion of a forwardly directed extension of said slot, a manually operable toggle lever mounted in said casing in front of said piston stem, a swingable part carrying a finger projecting into said slot to depress said piston stem against the opposition of the contents of said dash-pot cylinder, a spring adjustable by said toggle lever to cause said swingable part to move up or else down, means in part carried by said toggle lever and manually movable in relation thereto to swing said piston stem backwardly to a position wherein its aforesaid seat is brought into a subjacent relation to said finger preparatory to the depression of said piston stem by said finger, means carried by the casing to automatically swing said piston stem forwardly thereby releasing said pin from said seat after it has acted upon the latter to depress the piston, and circuit closing and opening means actuated by said swingable part.
2. The subject matter of claim 1 and, said means to swing said piston stem forwardly consisting of a cam lug positioned to be engaged by the descending piston stem.
3. Means for retarding the circuit-opening action of an electric switch comprising a casing, a dash-pot cylinder in the lower portion of said casing, a piston stem having a head operating in said cylinder, said piston stem having an upwardly directed seat formed upon it, a manually operable toggle lever mounted in said casing in front of said piston stem, a swingable part carrying a finger to engage said seat at times to depress said stem against the opposition of the contents of said dash-pot cylinder, a spring adjustable by said toggle lever from one to the other of each of two positions, said spring in one of said positions causing an upswing of said swingable part and in its other position causing a downswing thereof, means in part carried by said toggle lever and manually movable in relation thereto to swing said piston stem from its normal position to a position wherein its aforesaid seat is brought into a subjacent relation to said finger preparatory to the de-

pression of said piston stem by said finger, means carried by the casing to automatically swing said piston stem forwardly during the final portion of its downward travel under the urge of said finger to release it from said finger, and circuit closing and opening means actuated by said swingable part.

4. In combination, a movement retarding means, a casing whereon said means is mounted, a manually operable toggle lever mounted on said casing, a manually slidable member mounted in part axially within said lever and having an inwardly extending portion in an offset relation to the axis of said lever, circuit closing and opening means operatively connected with said offset portion of said slidable member, and means to retard the circuit opening operation of the switch, the latter means including a compressible and extensible spring which is connected with said offset portion of said slidable member, said spring being thrown off center by each swinging movement of said lever, said lever being swingably supported by pivots which are offset in relation to the axis of said lever in the same direction and to the same extent as the offset of the aforesaid slidable member.

5. A casing, a dash pot cylinder carried by said casing, a piston stem having a head operating in said cylinder, said stem being swingable a material amount without interfering with the functioning of its head within said cylinder; means to open and close an electric circuit, said

means including spaced apart terminals, a blade movable to and from a position for bridging the space between said terminals, and a switch lever operatively related to said blade, said means also including a part retardable by said piston stem; manually operable means to swing said piston stem from its normal position to the position wherein it performs its retarding function, the last recited means including a slidable member, a portion of which is contained in a groove in a wall of the casing, said groove having a contracted mouth portion overlying a part of said member to retain it in its operative position, and disengaging means carried by the casing automatically to swing said piston stem out of engagement with the aforesaid part which is retardable thereby, said disengaging means acting upon said piston stem during the final part of its movement toward said cylinder.

6. In a snap action electric switch having an auxiliary mechanism for manually converting the snap action into a delayed snap action; a circuit controlling handle, means for closing and opening a circuit from said circuit controlling handle while said auxiliary mechanism is maintained in an inactive position in either direction said handle is moved to open and close said circuit, and means carried by said handle to put said auxiliary mechanism into position for operation by the action of said handle in one of the directional movements.

EWING L. SHARP.
